US00D630729S

(12) **United States Design Patent**
Bierman et al.

(10) **Patent No.:** **US D630,729 S**
(45) **Date of Patent:** ** *Jan. 11, 2011

(54) **ACCESS DEVICE**

(75) Inventors: **Steven F. Bierman**, Del Mar, CA (US);
Richard A. Pluth, San Diego, CA (US)

(73) Assignee: **Access Scientific, Inc.**, San Diego, CA (US)

(**) Term: **14 Years**

(21) Appl. No.: **29/363,764**

(22) Filed: **Jun. 14, 2010**

Related U.S. Application Data

(63) Continuation of application No. 29/343,774, filed on Sep. 18, 2009, now Pat. No. Des. 617,893, which is a continuation of application No. 29/305,172, filed on Mar. 14, 2008, now Pat. No. Des. 601,242.

(51) **LOC (9) Cl.** **12-11**

(52) **U.S. Cl.** **D24/112**

(58) **Field of Classification Search** **D24/112-114, D24/108, 133, 186, 130; 606/181, 185; 604/264, 162, 232, 187, 160**

(57) **CLAIM**

The ornamental designs for an access device, as shown and described.

DESCRIPTION

FIG. 1 is a front side perspective view of an access device configured in accordance with a preferred embodiment of the present invention;

FIG. 2 is a top view of the access device shown in FIG. 1; FIG. 3 is a first side view of the access device shown in FIG. 1, the other side being a mirror image of the first side;

FIG. 4 is a bottom view of the access device shown in FIG. 1; FIG. 5 is a first end view of the access device shown in FIG. 1;

FIG. 6 is a second end view of the access device shown in FIG. 1;

FIG. 7 is a front side perspective view of an access device configured in accordance with another preferred embodiment of the present invention;

FIG. 8 is a top view of the access device shown in FIG. 7; FIG. 9 is a first side view of the access device shown in FIG. 7, the other side being a mirror image of the first side;

FIG. 10 is a bottom view of the access device shown in FIG. 7;

FIG. 11 is a first end view of the access device shown in FIG. 7; and,

FIG. 12 is a second end view of the access device shown in FIG. 7.

The features shown in broken lines depict environmental subject matter only and do not limit the claimed design.
